WING FLOAT

Filed May 12, 1932

FIG. 1

UNITED STATES PATENT OFFICE

2,009,344

WING FLOAT

Earl J. W. Ragsdale, Norristown, Pa., assignor to
 Edward G. Budd Manufacturing Company,
 Philadelphia, Pa., a corporation of Pennsylvania

Application May 12, 1932, Serial No. 616,786

12 Claims. (Cl. 244—2)

My invention relates to flying-boat structures and particularly to floats for supporting the wings thereof.

The objects of my invention include the provision of a wing float which shall be constructed substantially entirely of metal, that shall be strong and of light weight and that shall have its parts particularly constructed to facilitate spot welding.

Other objects include the provision of a float that shall offer substantially a minimum resistance to wind and water, that shall be water-tight and rust-proof and that shall have other advantages incident thereto.

Flying boats have heretofore been constructed with floats disposed laterally outwardly on the wings for supporting the same, while resting on the water, but such floats, to the best of my knowledge, have been constructed of materials subject to rust and disintegration, with the result that they became uncertain and dangerous in character, unless frequently inspected, and entailed the trouble and expense of renewal, besides having other objections.

In practicing my invention, I provide a float of hollow-shell character having an outer sheathing of extremely thin-gauge stainless steel and an internal frame, preferably also of stainless steel, particularly adapted to mount the float on a wing and to reinforce the float against forward and downward impact forces, and other features, as will hereinafter appear.

This structure is permanent so far as rusting, rotting and other effects of time, wear and weather are concerned, and is a substantial advance in its field.

Figure 1, of the accompanying drawing, is a side view of a float embodying my invention, one side wall sheathing being removed.

Figure 2 is an enlarged sectional view, taken substantially along the line 2—2 of Figure 1.

Figure 3 is an enlarged detailed view of a portion of the device shown in the upper right hand corner of Fig. 2, showing also, a portion of a wing to which the device is attached, and

Figure 4 is an exterior view of the assembled structure.

The device comprises, in general, a top wall 1, a bottom wall 2, side walls 3, laterally-spaced longitudinal side and bottom stringers 4 and 5 respectively, transverse frame members 6, central longitudinal bottom beams 7 and 8, a forward upper support 9 and a main support including a pair of front beams 10 and a pair of rear beams 11.

The side walls 3 are preferably constructed of continuous sheet form, from the rear, along one side, slightly curved about the bow 12 and along the other side to a rear edge 14, where the ends of the sides are spot welded together in flat side-by-side relation. Top and bottom edge stringers 15 and 16, respectively, of L-section, follow the contour of the meeting edges of the top and side walls for which they constitute angle braces between the sides 4 and portions of the top and bottom walls projecting outwardly beyond the sides.

The top and bottom wall members 1 and 2 substantially conform in perimetral contour to the horizontal-plane contour of the stream-line 15 sides; the bottom wall 2 curving forwardly and upwardly from a position between its mid and aft sections, and the parts 1, 2, 3, 14, 15 and 16 being spot welded to each other. Also, the top wall 1 conforms to the bottom contour of the 20 wing on which it is mounted to provide a symmetrical closed structure and to ensure against interference, or localized stresses, between the float and the wing.

The side stringers 4, of channel section, are 25 spot welded to the sides, in bottom engagement therewith and in free floating relation thereon, that is, they are not attached to any other part of the float, and they serve solely as stiffening means for the relatively extensive thin sheets 3. 30

Under normal service conditions when the flying boat, on which the float is mounted, descends to the water, it does so at a forward-and-downward angle, in view of which, the elements 6 to 11, inclusive, are arranged to resist the impact forces resulting therefrom. That is, the frame is arranged to have its major bracing effect against the rearward and upward reactionary forces.

When the float is at rest, its major function is 40 vertical support, or to provide buoyancy in view of which the float sheathing is extended forwardly and rearwardly from the major frame support and out of the zone of the main impact forces; the shell or sheathing being sufficient to 45 resist the slight forces therein when the ship is at rest.

To simplify the frame structure and to permit it to be constructed from parts of standard shapes, rather than have these parts conform to 50 the curved contour of the bottom wall, the beams 7 and 8 are disposed substantially along chords of the bottom-wall curve and are connected to the bottom wall, between the ends of the beams 7 and 8, by the transverse frames 6, gussets 17, 55

between the longitudinal center and the transverse beams, and gussets 19, between the transverse beams and the longitudinal bottom stringers.

- 5 The gussets 17 and 19 are each of thin sheet metal bent to channel-shape having tapering sides providing spot-welding side-wall areas at the deeper end of the channel and a spot-welding bottom-wall area at the shallow end of the channel; the gussets 17 being of varying dimensions to adjustably fit the straight beams 1 and 8 to the curve of the bottom 2.

The transverse frames or beams 6, of channel or box section, are supported, from above, only at the centers thereof, by the beams 7 and 8 from which the beams 9, 10 and 11 project upwardly to positions at the intersections of the top and side walls of the float; the beams 9, 10 and 11 being also of channel or box section. The arrangement of the beams 10 and 11 provides an angle brace of substantially V-shape in transverse contour as viewed in Fig. 2, and of inverse V-shape as viewed in Fig. 1, providing substantial transverse and longitudinal support above and below, respectively.

There are two of the front upright beams 9 also, arranged in V-relation in a vertical transverse plane of the float.

Plate gussets 20 of substantially V-shape are spot welded to the lower-end transverse sides of the beams of each pair of beams 10 and 11 and plate gussets 22 are spot welded to the outer sides of the beams 10 and 11 and to the inner sides of the channel-section beams 7 and 8.

35 Adjacent to the cover 1, the beams 10 meet the beams 11 to which they are secured by gussets 24 each having portions spot welded in flat-side engagement with the side wall 3 and with the transverse sides of the beams 10 and 11. 40 Exterior gussets 26 are each of substantially channel section and have a bottom wall 27 connected to the beams 10 and 11 and spot welded to the gussets 24, through the walls 3 and the gussets 20. The gussets 26 each have a closed-end wall 28 for attachment to a main supporting frame or rear spar 30 of a flying boat wing 32, and sides sloping from the closed end 28 toward the opposite end of the gusset which is open. The forward upright support 9 is similarly 45 secured and braced at its upper and lower ends, and adapted for attachment to the front spar.

The structure is remarkable in the simplicity of its outer surface, having no rods, bars or other small parts but being constituted substantially 55 entirely of expansive smooth contoured stream line and impact surfaces. By eliminating upright braces for the side walls and substituting therefore the floating braces 4, the number of parts and the weight are substantially reduced, 60 without the sacrifice of necessary strength.

The arrangement of the beams 7 and 8 whereby, although they are standard straight beams, they support the curved bottom 2, the center support for the longitudinal center bottom beams, the inverse V-structure of the frame, the arrangement of parts whereby they are connected almost exclusively by spot welding, the employment of stainless steel, and other features, render 65 the device particularly durable, proof against deterioration, effective in operation and an improvement generally in the art to which it relates.

70 While I have shown and described a particular form of my invention, changes may be effected therein without departing from the spirit and

scope thereof, as set forth in the appended claims.

I claim as my invention:

1. In combination, in a flying boat, a wing, and a float including outer side and bottom-wall sheathings, a frame including a beam intercepting the side-wall sheathing adjacent to the top edge thereof, and securing means including a gusset secured to the beam through the sheathing and to a wing spar.

2. In combination, in a flying boat, a wing, and a float having a top wall sheathing conforming to, and closely fitting, the under side of the wing, a side wall sheathing of stream-line contour, a frame having a portion adjacent to the intersection of said top and side walls, and a gusset connected to the wing spar and to said frame portion through said side-wall sheathing.

3. A flying-boat wing float comprising side sheathing extending continuously from an aft edge, forward on one side, about the bow and aft 20 on the other side to provide another edge in side-by-side relation to said first edge.

4. A flying boat wing float including sheathing comprising a transversely flat top sheet, a longitudinally curved but transversely flat bottom sheet, and side sheathing connecting the top and bottom sheets, extending continuously from a vertical aft edge forward on one side, about the bow and aft on the other side to provide another edge in side by side relation to the first edge. 30

5. A flying boat wing float comprising a sheathing constituting a longitudinally-curved transversely flat bottom wall, an inner support including rigid transverse bottom beams spaced fore and aft, and means supporting said beams only 35 at the centers including a rigid bottom element extending along a chord of the curve, and thin sheet side walls disposed in freely suspended position between the top and bottom of the float on said inner support.

6. In combination, in a flying boat, a hollow wing structure including inner supporting means, and a hollow-body float including a rigid inner support of V-section viewed aft secured at its upper ends to said wing supporting means, a 45 rigid horizontal cross brace at the bottom of said section, and thin sheet side walls secured to said section and to said brace in freely suspended relation therebetween.

7. A flying-boat wing float comprising a 50 sheathing including a transversely flat bottom wall and freely suspended side walls, and a supporting frame therefor including transverse and longitudinal bottom frame members and a structure for tying the float to a wing having right 55 angularly related substantially V-profiles inverted relative to each other, the V-frames terminating at the bottom on the central portion of the bottom frame members and at the top along the sides of the float in the regions of joinder 60 to a wing.

8. In combination, in a flying boat, a wing, and a float including a sheathing having a transversely flat bottom wall and side walls freely suspended between top and bottom edge margins 65 thereof, a frame embodying a central bottom beam and upwardly extending beams between said bottom beam and the sides of the float disposed longitudinally in substantially V-relation having their upper ends secured to a wing spar 70 therealong.

9. In combination, in a flying boat, a wing including a spar, and a float including a frame embodying beams depending from the wing spar at spaced positions therealong and diagonally join- 75

ing the wing spar with a longitudinal bottom center beam, said beam ending short by a substantial distance from one end of the float, and transverse frames on the center beam supporting the bottom wall of the float.

5 10. A wing float comprising a frame including a longitudinal center bottom beam, a fore support of transverse V-shape, and an aft support of longitudinal inverse V-shape and transverse V-shape, each of said supports bracing the center beam to a point on the float for connection with a wing spar.

10 15. A flying boat wing float comprising a sheathing including freely suspended side and transversely flat bottom walls, and a frame including transverse members on the bottom wall, a longitudinal central member secured to said

transverse members, the remainder of the frame having a frame connection to the transverse members only through said central member and extending to points of connection with a wing spar.

5 12. A flying boat wing float comprising a sheathing including freely suspended upwardly converging side and transversely flat bottom walls, and a frame ending short of an end of the float by a substantial distance and including longitudinal bottom stringers, transverse beams on the stringers, a longitudinal center beam on said transverse beams, and members extending upwardly from the center beam to points of connection to a wing spar and constituting the only 10 frame bracing for the frame parts therebelow.

15 EARL J. W. RAGSDALE.
